ABSTRACT: The force or degree of compression of the spring is adjusted by rocking the lever about its axis A-B by means of the manually operated cam acting on the lever at D. Calibration is effected by adjusting the screw at B to rock the lever about axis A-D. Any tool forces applied to the adjusting screw during adjustment cannot be transmitted to the spring to adversely affect calibration.

ADJUSTING AND CALIBRATING OF PRESSURE SWITCHES

BACKGROUND OF INVENTION

Pressure switches have been provided with cam-actuated levers for adjusting the spring force of the pressure switch and, thus, the level to be sensed by the switch. Since the nature of the device requires calibration after assembly, the lever was provided with a calibrating screw. Tool forces applied to the calibrating screw could be transmitted to the spring and affect the calibration. This could result in improper calibration or prolong the calibration process.

SUMMARY OF INVENTION

The present construction provides a lever which can be adjusted about an axis defined by a fixed pivot point A and a pivot point B which is also an adjusting screw. The lever is in the general form of a plate with the cam acting at a point D remote from the adjusting axis. The lever acts on the spring at a fourth point C remote from the other points. When the adjusting screw at B is moved, the lever rocks about axis A-D and moves point C to calibrate the spring. Tool forces applied to the screw during calibration cannot influence the spring. Therefore, the calibration process is more accurate and faster.

DESCRIPTION OF DRAWINGS

FIG. 1 is a top plan view of the apparatus.

FIG. 2 is an elevation taken from the right in FIG. 1.

FIG. 3 is a partial elevation taken from the right in FIG. 2.

FIG. 4 is a perspective with some parts broken away for clarity.

DESCRIPTION OF PREFERRED EMBODIMENT

The details of the pressure switch are not shown here. It is only important to know that the compression of the spring 10 is to be adjusted in use and the unit should be calibrated at the factory so the actual compression of the spring corresponds to the indications associated with the manual adjusting arrangement. The spring 10 is housed in a plunger 12 which lies under one corner C of the generally rectangular level 14. The lever is pivoted at A in the fixed bracket 16 while another corner B is provided with a finger 18 which is formed and notched at 20 to fit over and be guided by the adjacent bracket portion 22 which carries the calibrating screw 24 against which the finger 18 bears by reason of the bias of spring 10. This point can be called B. The fourth corner of the lever is formed to provide a follower 26 bearing at D against the cam 28 pivoted at 30 in the bracket and actuated by arm 32. The spring force tries to push lever 14 up at C which pushes down at A and up at B and

5 D. The lever is held against calibrating screw 24 and Cam 28 by the spring.

When the arm 32 is moved, it rotates the cam 28 about its pivot 30 to raise or lower lever 14 at D. Since A and B are fixed, the lever 14 rocks about the axis determined by A-B to adjust C and the spring 10. If the calibrating screw 24 is adjusted, point B is raised or lowered and the lever 14 must rock about axis A-D to thereby adjust C and spring 10. Since the screw is supported by the bracket, any tool forces applied to the screw cannot influence the force of spring 10. Calibration of the spring is, therefore, isolated from undesired influences.

10 An advantage of this design is that an extra low setting of the spring can be achieved by allowing the lever to strike an adjustable stop which can be accurately calibrated for the specified value.

15 Since calibration tool forces cannot affect the spring force being calibrated, this design lends itself to advanced or automated calibration techniques.

20 For simplicity, A-B and C-D are generally parallel. This avoids motion multiplying effects having to be considered in designing the cam.

I claim:

25 1. Apparatus for adjusting and calibrating a spring comprising:

a bracket,
a lever mounted on the bracket for pivoting about an axis A-B where
point A is a fixed pivot, and
point B is an adjustable calibrating screw spaced from A,
30 a compressed spring to be adjustably loaded and acted upon by said lever at a point C spaced from A and B and not on the A-B axis,

an adjusting device acting on the lever at a point D spaced from A, B and C and not on the A-B or A-C axis whereby movement imparted to the lever at D by the device pivots the lever about the A-B axis and causes movement at C to adjust the compression of the spring;
adjustment of the calibrating screw B being effective to pivot the lever about the A-D axis and cause movement at C to adjust the compression of the spring.

40 2. Apparatus according to claim 1 in which A-B and C-D are generally parallel.

3. Apparatus according to claim 1 in which the calibrating screw is carried by the bracket and acts on the lever while the compressed spring urges the lever against the screw.

4. Apparatus according to claim 3 in which the lever is urged against the adjusting device by the spring.

5. Apparatus according to claim 4 in which the adjusting device is a cam pivoted on the bracket.
